UNITED STATES PATENT OFFICE

154,247

DESIGN FOR A HAND LUGGAGE CASE
OR THE LIKE

Charles Doppelt, Chicago, Ill.

Application May 7, 1947, Serial No. 138,868

Term of patent 14 years

(Cl. D87—5)

To all whom it may concern:

Be it known that I, Charles Doppelt, a citizen of the United States, residing at Chicago, in the county of Cook and State of Illinois, have invented a new, original, and ornamental Design for a Hand Luggage Case or the like, of which the following is a specification, reference being had to the accompanying drawing, forming part thereof.

Fig. 1 is a perspective view of a hand luggage case or the like showing my design.

Fig. 2 is a bottom plan view of same.

The sides of the luggage case not shown are substantially like the corresponding sides shown.

I claim:

The ornamental design for a hand luggage case or the like, as shown and described.

CHARLES DOPPELT.
